PORTABLE HAIR DRYER

Ivar Jepson and Robert O. Ernest, Oak Park, Ill., assignors to Sunbeam Corporation, Chicago, Ill., a corporation of Illinois

Filed Aug. 10, 1959, Ser. No. 57,105

Term of patent 14 years

(Cl. D86—10)

Fig. 1.

Fig. 2.

Fig. 3.

Fig. 4.

Fig. 1 is a front perspective view of a portable hair dryer embodying our new design;

Fig. 2 is a top plan view thereof;

Fig. 3 is a left side elevational view thereof the right side being a mirror image of this left side; and

Fig. 4 is a back view thereof.

We claim:

The ornamental design for a portable hair dryer, as shown and described.
